CLAIM

The ornamental design for a manicure kit, as shown and described.

DESCRIPTION

FIG. 1 is a front, right and bottom perspective view of the manicure kit in an assembled state, showing my new design.

FIG. 2 is a rear, left and top perspective view thereof;

FIG. 3 is a front, right and bottom perspective view of the first component of the manicure kit;

FIG. 4 is a rear, left and top perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a front, right and bottom perspective view of the second component of the manicure kit;

FIG. 12 is a rear, left and top perspective view thereof;

FIG. 13 is a front view thereof;

FIG. 14 is a rear view thereof;

FIG. 15 is a left side view thereof;

FIG. 16 is a right side view thereof;

FIG. 17 is a top plan view thereof;

FIG. 18 is a bottom plan view thereof.

FIG. 19 is a front, right and bottom perspective view of the third component of the manicure kit;

FIG. 20 is a rear, left and top perspective view of the third component thereof;

FIG. 21 is a front view thereof;

FIG. 22 is a rear view thereof;

FIG. 23 is a right side view thereof;

FIG. 24 is a left side view thereof;

FIG. 25 is a top plan view thereof; and,

FIG. 26 is a bottom plan view thereof.

The broken lines shown in the drawings illustrate portions of the manicure kit that form no part of the claimed design.
